OPPOSED PISTON PUMP

Erie P. Halliburton, Los Angeles, Calif., assignor
to Halliburton Oil Well Cementing Company,
Duncan, Okla.

Application October 1, 1949, Serial No. 119,190

3 Claims. (Cl. 103—159)

1

This invention relates to reciprocating pumps and more particularly to those having opposed pistons in the cylinders.

There has long been considerable demand for a sturdy pump, compactly built and of minimum weight and yet capable of delivering heavy liquids such as mud or cement slurry at high pressures. In designing pumps for oil field uses, many attempts have been made to increase the strength of various parts without unduly increasing the weight thereof. The problem is to provide a pump which is capable of moving heavy, viscous and sometimes abrasive liquids against thousands of pounds per square inch of pressure and still have a unit which is portable and not too long to be mounted conveniently on a truck.

A pump having a short connecting rod is desirable for such uses as those mentioned because of the high pressures encountered and because of the limitations imposed as to over-all length. To further reduce the over-all length of the pump and also because the liquids being moved often contain sand or other abrasives which cause wear on pistons and cylinders, a short crank and hence a short stroke is desirable.

However, as is well known, a short connecting rod in a pump causes the piston travel to depart considerably from simple harmonic motion. This departure causes liquid delivered by the pump to surge. Moreover, a short crank either reduces the capacity of the pump to deliver a large volume per unit of time or requires that the pump be operated at high speed.

Theoretically, an ideal pump, insofar as smoothness in operation in the delivery of liquid is concerned, would be one in which the ratio of the connecting rod to the crank is very large. The piston movement would then approach that of simple harmonic motion if the crank were rotated at a constant velocity.

In designing pumps having a single piston in each cylinder, these considerations have resulted in a comprise. The connecting rod has usually been made from 4 to 6 times the length of the crank. Lesser ratios of connecting rod to crank reduce the over-all length of the pump but cause such surges to develop in the liquids being pumped as to be regarded as contrary to good engineering practice. Greater ratios reduce the surge, and from that viewpoint are highly desirable, but increase the required length of the pump beyond reason and increase the weight.

In accordance with the present invention, it is proposed to provide a light weight, slow speed pump having a short connecting rod and a short

2

crank but with piston displacement approaching very closely simple harmonic motion, so as to deliver a large volume of liquid per unit of time at a high pressure and with very little surge. This is accomplished by providing opposed pistons in each cylinder and by so mounting each cylinder as to cause it to oscillate about a pivot point. The arrangement is such that the combined movement of the two pistons and the cylinder creates liquid movement approaching very closely that which would be obtained by an ordinary pump with a connecting rod of great length.

The term "opposed pistons" as used herein, means that the two pistons in each cylinder of the pump travel toward and away from each other to effect changes in volume or displacement in the cylinder. The pistons do not accelerate or travel in synchronism, however. The cylinder itself is caused to move laterally during the stroke of the pistons and the combined movement of the two pistons and the cylinder is such as to cause the resultant displacement or relative piston travel in the cylinder to be approximately the same as that which would be obtained if simple harmonic motion were imparted to a single piston in a cylinder.

One way in which the invention may be carried out is illustrated in the accompanying drawings in which:

30 Fig. 1 is a fragmentary view in side elevation of one cylinder and the associated elements of a triplex pump constructed in accordance with the present invention;

35 Fig. 2 is a fragmentary plan view of the pump of Fig. 1;

Fig. 3 is a view in vertical cross-section of one of the cylinders of the pump of Fig. 1;

Fig. 4 is a view in transverse cross-section through a portion of the pump of Fig. 1, the view being taken on the line 4—4 of Fig. 3;

45 Figs. 5, 6, 7, and 8 are diagrammatic representations of an oscillating cylinder in cross-section with opposed pistons therein connected to cranks spaced 180 degrees on a common crankshaft, the views representing the relative position of the parts of the pump of Figures 1 to 4 at 90 degree intervals of rotation of the crank shaft and illustrating the principles of the invention; and

50 Fig. 9 is a chart in which crank travel is plotted against piston travel and illustrating the advantages of the present invention.

Referring to the drawing in detail and first to the structure shown in Figs. 1 to 4 inclusive, it will be seen that a reciprocating pump is there shown as provided with a plurality of cylinders 11 mount-

ed upon a frame 12. All of the cylinders are alike and each is provided with two plungers or pistons and these being designated 13 and 14. For convenience, the piston 13 may be referred to as the crank-end piston and the piston 14 as the head-end piston although the cylinder 11 actually has no head, being exactly alike at both ends. Suitable packing, such as the chevron washers shown at 15 in Fig. 3 is provided between the pistons and the cylinder 11.

Each cylinder 11 is mounted in the frame 12 for oscillating movement. To this end, each cylinder is provided with trunnions 16 mounted in supporting bearings 17. Some of the trunnions 16 are hollow, as shown in Fig. 4 and these provide a passageway for conducting liquid from the cylinder into the discharge opening 18 in the bearing 17. Chevron packing 19 is provided between the trunnions 16 and the bearings 17.

All of the trunnions 16 are offset vertically from the center line of the cylinders 11 which they support, so that the cylinders swing like a pendulum.

As shown in Figs. 3 and 4, inlet valves 20 are provided beneath each cylinder 11, liquid to these being supplied through a hose or other flexible conductor as shown at 21. Discharge valves 22 are provided between the cylinder 11 and the trunnions 16.

Oscillating movement of each cylinder 11 is controlled by its piston 13. As shown in Fig. 3, each piston 13 is directly connected with the strap 23 around a disk 24. At a point offset from its center, disk 24 is integrally connected to crankshaft 25. The crankshaft 25 is mounted in suitable bearings 26 in the frame 12. Thus, it will be seen that the strap 23, disk 24 and crankshaft 25 constitute an eccentric. An ordinary crank could, of course, be used instead of the eccentric shown, the two being kinematically equivalent, and in the diagrams of Figs. 5 to 8 cranks have been shown for ease in illustrating the operation.

In addition to the provision of one eccentric disk 24 for each crank-end piston 13, there are two similarly constructed eccentric disks 27 integrally connected to the crankshaft 25 for each head-end piston 14. In the arrangement shown there are thus three eccentrics or cranks for each cylinder, and these may be said to be a set of cranks. There are as many sets of cranks as there are cylinders. To avoid confusion in illustrating, Fig. 1 shows only one cylinder 11 with its piston actuating arrangement but it will be understood that all of the cylinders, no matter how many are used, have the same kind of piston actuating means. As shown in Fig. 1 and also as shown in Fig. 2, each head-end piston 14 is pivotally joined by cross connecting pin 30 to two connecting rods 28 which are in turn directly connected to their respective straps 29 on eccentric disks 27.

The disks 27 for each cylinder are mounted alike and are spaced 180 degrees upon the crankshaft 25 from their cooperating disk 24 for the crank-end piston 13. Only the piston 13 controls oscillating or swinging movement of the cylinder 11 as the crankshaft is rotated. The disks 27 drive the piston 14 through the connecting rods 28 and cross connecting pin 30 but the motion of the piston 14 with respect to the cylinder 11 is different from that of piston 13 with respect to the cylinder 11. The advantages of the present invention depend upon certain principles of operation in which the opposed pistons move in a

novel way, as will be apparent from a consideration of Figs. 5 to 9, inclusive, of the drawing.

Figs. 5 to 8 illustrate the basic principles of the invention. In these figures the same reference characters are used as those which designate corresponding parts in the structure shown in Figs. 1 to 4.

These figures illustrate the sequence of operation, during one complete revolution of the crank shaft, of the various parts of a single cylinder pump constructed in accordance with the invention. In these figures the crank 24 is shown as being of the same length as the crank 27. The pivot point for the cylinder 11 (corresponding to the center of the trunnions 16 in Figs. 1 to 4) is designated 31. The exact center of the cylinder 11 is designated 31. It will be seen that the distance from point 16 to point 31 is the same as the length of crank 24. It has been found by calculation that with these dimensions a very close approach to the desired simple harmonic motion is obtained and it has been found by experience that a pump having remarkable smoothness of operation is obtained when the parts are so constructed, but the advantages of the invention may be obtained, at least to some extent, if these dimensions are not followed exactly.

Fig. 5 shows the position of the parts when the cylinder 11 and cranks 24 and 27 are all horizontal with the pistons 13 and 14 near their inner positions. However, neither piston is then at its individual extreme inner position in the cylinder, as will be explained later. Except for a slight clearance, the net or resultant piston displacement in the cylinder 11 is zero when the parts are in the position of Fig. 5, and the pump has just completed its discharge or pump stroke. In traveling from the position shown in Fig. 5 to the position shown in Fig. 7, the pump makes its intake or suction stroke and in traveling from the position shown in Fig. 7 back to the position shown in Fig. 5, the pump makes its discharge stroke.

Assuming that the crankshaft 25 is rotated, as shown by the arrow, 90 degrees to the right from the position shown in Fig. 5, the parts then take the position shown in Fig. 6. As the outer end of piston 13 is raised, the cylinder 11 is caused to swing to the right. The pistons are both leaving the center 31 of the cylinder by the time the parts are in the position shown in Fig. 6 but the piston 14 travels faster than the piston 13 during this 90 degrees of rotation. In fact, relative to the cylinder, the piston 13 travels slightly to the left of its position shown in Fig. 5 before it moves to the right to take the position shown in Fig. 6. The initial cylinder motion to the right in Fig. 5 is greater than the initial motion of piston 13 in that direction. It will be seen that as a result of the cylinder motion, even by the time the parts take the position shown in Fig. 6, the piston 13 is still much closer to the center point 31 than is the piston 14.

Upon rotation of the crankshaft 25 another 90 degrees, as shown in Fig. 7, both pistons are near their outer positions but neither is at its individual extreme outer position, as will be explained later. Both are then equi-distant from the center point 31, and the net or resultant piston displacement in the cylinder is then a maximum and the intake stroke is completed.

Upon rotation of the crankshaft 25 the next 90 degrees, the parts take the position shown in Fig. 8. The cylinder 11 has now been forced to

swing to the left by the piston 13. The piston 14 is then closer to the center point 31 than is the piston 13.

This construction causes variations in internal volume in the cylinder 11 which are remarkably close to ideal. As indicated above, an ideal single piston reciprocating pump, insofar as smoothness of operation is concerned, would be one in which the piston traveled with simple harmonic motion. If the piston is actuated by a connecting rod and crank this is impossible to attain. All such pumps depart considerably from the ideal. On the intake or suction stroke of the pump this is perhaps not so important but upon the discharge stroke, especially in extremely high pressure pumps, departure from simple harmonic motion is very undesirable.

To illustrate and compare, in Fig. 9, angular crank travel for the discharge stroke of two pumps is plotted against piston travel. The heavy curve 32 is the theoretic or ideal. It is a curve of simple harmonic motion or the motion obtained by the projection of uniform motion of the crank pin of a pump on a diameter of the circle described by it. It is the motion which would be imparted to a piston in a fixed cylinder if the piston were connected to the crank pin by a connecting rod of infinite length with the crank pin rotating at a constant angular velocity.

The lighter curve 33 of Fig. 9 illustrates the actual piston travel in a well designed single piston pump driven at a constant velocity. The particular pump selected for computing the data used to make this curve is a modern pump used by the Halliburton Oil Well Cementing Co., and known as Model T-10. The ratio of connecting rod to crank is 4.2.

The dashed line curve 34 of Fig. 9 shows the relative or the effective piston travel with respect to the cylinder of a comparable opposed piston pump constructed in accordance with the present invention. Dotted line curves 35 and 36 show the individual travel of the two pistons 13 and 14 with respect to the cylinder 11 of this pump. Values on curve 34 are the average or one-half 45 the sum of the values on dotted line curves 35 and 36. It will be observed that the curve 35 moves down beneath the zero point of piston travel at the beginning of the discharge stroke. In other words, with the parts in the position shown in Figure 7, the piston 13 travels away from the center point 31 of the cylinder for a short time at the beginning of the pump or discharge stroke. If it were the only piston in the cylinder the piston displacement in the cylinder would be increasing instead of decreasing as the cranks start to rotate from the position shown in Fig. 7.

But while the piston 13 is traveling away from the center of the cylinder 11 during the initial part of the discharge stroke of the pump, the piston 14 is traveling toward the piston 13 at a greater rate as shown by the slope of the lower part of curve 36 and the actual result of the combined motion of the two pistons and the cylinder is that the piston displacement or volume between pistons in the cylinder is decreased as shown on the curve 34.

As mentioned above, a peculiarity of this pump is that the pistons do not travel in unison. The individual piston travel is such that each is not at the end of its travel relative to the cylinder when the cranks are in the horizontal positions illustrated in Fig. 5 and Fig. 7, even though the piston displacement is at a minimum and a maximum respectively when the cranks are in the 75

positions shown in Fig. 5 and Fig. 7. The piston travel relative to the center of the cylinder is quite different than it is relative to any other fixed point on the frame. Relative to the cylinder, the piston 13 does not reach the outer end of its path of travel in the cylinder (the lowest point on the curve 35 in Fig. 9) until after the cranks have rotated some distance beyond the position shown in Fig. 7, while the piston 14 reaches the outer end of its path of travel in the cylinder before the cranks have reached the position shown in Fig. 7. Similarly, at the end of the discharge stroke, the piston 14 reaches the inner end of its path of travel in the cylinder (the highest point on the curve 36 in Fig. 9) before the cranks have reached the position shown in Fig. 5. Likewise, the piston 13 reaches the inner end of its path of travel after the cranks have rotated some distance beyond the position shown in Fig. 5. The pistons start and end their strokes in the cylinder at different times but the net or resultant effect of their strokes is that the discharge stroke of the pump starts when the parts are in the position shown in Fig. 7 and ends when the parts are in the position shown in Fig. 5.

As shown by curve 34, throughout its entire discharge stroke, the pump has a net piston displacement which approaches very closely that of the simple harmonic motion curve shown at 32. In all of the curves, it is assumed that the crank-shaft is being rotated at a uniform velocity. If there is any variation in velocity during the stroke, of course these curves do not hold true.

The lack of uniformity or synchronism of individual piston movement illustrated by curves 35 and 36 is due to the fact that the pivot point 16 of cylinder 11 is offset from the center point 31 thereof a distance equal to the eccentricity of disk 24 (or crank length for the driving means for piston 13). If an opposed piston pump were constructed with the points 16 and 31 a different distance apart, relative to the eccentricity so that the cylinder 11 did not swing horizontally to the same extent as that illustrated, a different net or resultant curve would be obtained. Such an opposed piston pump would be superior to a single piston pump but it would not have as much freedom from surge as the pump shown.

It is obvious that if an opposed piston pump is constructed with the points 16 and 31 spaced differently from that at which the greatest freedom from surge is attained, that is, when they are spaced some distance other than the length of the crank, the advantages of the invention may still be attained to a certain extent or degree. Mechanical considerations may make it desirable to employ dimensions other than those here indicated as the most desirable. It is obvious therefore that while only one embodiment of the invention has been illustrated and described, various changes may be made in the arrangement and construction without departing from the spirit of the invention or the scope of the annexed claims.

I claim:

1. In a reciprocating pump, a frame, a crank-shaft mounted for rotation on the frame, cranks on the crankshaft angularly spaced substantially 180 degrees, a cylinder, trunnions fixed to the cylinder and offset from the center of the cylinder, bearings for the trunnions secured to the frame whereby said cylinder is mounted for oscillatory movement on the frame, two opposed

pistons in the cylinder and means connecting each piston to one of said cranks.

2. In a multiple cylinder reciprocating pump, a frame, a crankshaft mounted for rotation on the frame, a plurality of sets of cranks, each set having at least two cranks on the crankshaft angularly spaced substantially 180 degrees, a plurality of cylinders, one for each set of cranks, trunnions fixed to the cylinders and arranged in line and offset vertically from the centers of the cylinders, bearings for the trunnions secured to the frame whereby each cylinder is mounted for individual oscillation on the frame, two opposed pistons in each cylinder, and means connecting each piston to at least one crank on the crankshaft.

3. In a reciprocating pump, the combination of a frame, a crankshaft mounted for rotation thereon, a plurality of cranks on the crankshaft angularly spaced substantially 180 degrees, a cylinder, means for pivotally mounting the cylinder for oscillation on the frame, said means consisting of trunnions offset vertically from the center of the cylinder whereby the cylinder swings

horizontally and arcuately on said trunnions like a pendulum, and two opposed pistons in the cylinder, one of which is directly connected to one of said cranks on the crankshaft and the other of which is connected to another of said cranks on the crankshaft through a connecting rod.

ERLE P. HALLIBURTON.
